US0D1087655S

(12) **United States Design Patent** (10) **Patent No.:** **US D1,087,655 S**
(45) **Date of Patent:** **** Aug. 12, 2025**

(54) **CURTAIN ATTACHMENT**

- (71) Applicant: **Bannack Medical LLC**, Gilbert, AZ (US)
- (72) Inventors: **Arlen Olsen**, Gilbert, AZ (US); **Joel Price**, Germantown, MD (US); **Joshua Olsen**, Logan, UT (US)
- (73) Assignee: **BANNACK MEDICAL LLC**, Gilbert, AZ (US)
- (**) Term: **15 Years**
- (21) Appl. No.: **29/940,804**
- (22) Filed: **May 6, 2024**

Related U.S. Application Data

- (62) Division of application No. 29/778,609, filed on Apr. 14, 2021, now Pat. No. Des. 1,032,236.
- (51) **LOC (15) Cl.** **06-10**
- (52) **U.S. Cl.** ..... **USPC D6/580**
- (58) **Field of Classification Search**
USPC ..... D8/18, 105, 349, 354, 356, 367, 368, D8/369; 248/341; 224/217; 24/1, 702; 160/330; 16/87.2, 93 D; D6/575-581
CPC A45F 5/021; A44B 13/0029; F16B 45/00; F16M 13/02
- See application file for complete search history.

(57) **CLAIM**

The ornamental design for a curtain attachment, as shown and described.

DESCRIPTION

FIG. 1 is a front perspective view of a curtain attachment showing our new design;

FIG. 2 is a second perspective view thereof;

FIG. 3 is a first side view thereof;

FIG. 4 is an opposite side view thereof;

FIG. 5 is a front view thereof;

FIG. 6 is a rear view thereof;

FIG. 7 is a top view thereof; and,

FIG. 8 is a bottom view thereof.

The broken lines in the drawings depict portions of the curtain attachment that form no part of the claimed design. Additional broken lines in FIG. 1 depict environmental subject matter or symbolic breaks that form no part of the claimed design.

1 Claim, 5 Drawing Sheets
